FOOD STORAGE CONTAINER OR THE LIKE

Alfred Pete Curry, 220 W. 111th Place, and Daniel W. Everage, 12026 Athens Way, both of Los Angeles, Calif. 90061

Filed Nov. 27, 1968, Ser. No. 14,707

Term of patent 14 years

Int. Cl. D7—01

U.S. Cl. D44—6

FIG. 1 is a perspective view of a food storage container or the like showing our new design;

FIG. 2 is an enlarged scale top plan view;

FIG. 3 is an elevational view thereof; and

FIG. 4 is a bottom plan view.

We claim:

The ornamental design for a food storage container or the like, substantially as shown.
